(57) **CLAIM**

I claim the hooded garment, as shown and described.

DESCRIPTION

FIG. 1 is a front perspective view of a hooded garment showing my new design;

FIG. 2 is a rear perspective view thereof;

FIG. 3 is a rear perspective view of a second embodiment thereof;

FIG. 4 is a third embodiment of a hooded garment showing my new design;

FIG. 5 is a rear perspective view of the garment of FIG. 4; and,

FIG. 6 is a rear perspective view of a fourth embodiment of the garment of FIG. 4.

The broken lines on the surface of the hooded garment in FIGS. 1–3 represent stitching.

The broken lines shown inside the opening of the hood, and the broken lines showing a raised portion in the top center of the hood and extending down the hood's rear, in FIGS. 1–6, are included for the purpose of illustrating environmental structure and form no part of the claimed design.
